UNITED STATES PATENT OFFICE.

JACOB P. TETER, OF INDIANAPOLIS, INDIANA.

SIPHON-DREDGE.

1,264,223.

Specification of Letters Patent. Patented Apr. 30, 1918.

Application filed December 8, 1916. Serial No. 135,766.

To all whom it may concern:

Be it known that I, JACOB P. TETER, a citizen of the United States, and a resident of Indianapolis, county of Marion, and State 5 of Indiana, have invented a certain new and useful Siphon-Dredge; and I do hereby declare that the following is a full, clear, and exact description thereof, reference being had to the accompanying drawings, in which 10 like letters refer to like parts.

This invention relates to a means for dredging the bottom of streams primarily to obtain gravel and sand. To accomplish this the principle of the siphon is used so that 15 the sand or gravel from the bottom of the stream may be sucked into a pipe and carried to the place of delivery through the suction and power created by the flow of water through the siphon.

20 The full nature of the invention will be understood from the accompanying drawings and the following description and claims:

In the drawings, Figure 1 is a side elevation showing a stream of water in cross section. Fig. 2 is a plan view looking down. Fig. 3 is a central longitudinal cross section taken on the line 3—3 of Fig. 2.

In the drawings, there is shown a stream 30 10 having a bed 11 and bank 12. There is a siphon consisting of a pipe line 13 having its end 14 submerged under water and extending over the bank to an elevation below the bed of the stream. A valve 15 is provided in the pipe line at the water level.

There is a valve 16 located in said pipe below the water level. Adjoining the siphon there is a dredging pipe 17 which extends downwardly to the bed of the stream so that 40 it will be in position to draw gravel or sand through its lower end by means of the suction of the siphon. On the end of said dredging pipe there is a screen 18 which sifts the sand and gravel so as to grade it. A cable 45 19 or other suitable means is secured thereto so that its position may be changed from time to time to operate a new section of the bed. Between the end 14 of the siphon and the junction of the dredging pipe there is a

50 water pump 20 adapted to pump water from the stream through the pipe 21 into the siphon in order to start its operation, said pump being provided with a valve 22. The lower outlet 23 of the siphon is reduced so

as to cause the rush of the water and gravel 55 to be retarded long enough for the finer gravel and the sand to pass through the screen 24 in the bottom of the siphon, into a pipe 25 which carries it to additional grading screens, not shown. A valve 27 is 60 provided between the pump 20 and the dredging pipe 17 so that the pump and the end 14 may be cut off, if desired, and the siphon continue to operate only through the dredging pipe 17. The valve 27 is also provided 65 with an air vent 50 which may be opened while the siphon is being filled, and closed so that it will continue to operate.

There is a valve 26 in the dredging pipe near the water level which is closed until 70 after the operation of the siphon commences, when it is opened so that the dredging pipe will be operated.

The operation of the siphon is as follows:

The air vent 50 of the valve 27 is opened 75 and the valves 15 and 16 are closed. The pump 20 is then started so that it will force water from the stream into that section of the siphon between said valves, forcing the air therein out through the air vent. When 80 this portion of the siphon is filled with water, the air vent is closed, and the valves 15 and 16 are opened, after which the operation of the pump 20 may be discontinued. The suction of the water that has been forced 85 into the siphon, passing down the incline thereof, will draw more water through the inlet 14 so that a constant passage of water will continue to flow through the siphon. The power and suction exerted by this flow 90 of water will also operate to produce a suction through the dredging pipe 17 to the bed of the stream so that the sand and gravel will be drawn into the siphon and carried out to its dumping place.

95 The invention claimed is:

A siphoning mechanism for removing gravel from the bed of a body of water comprising a siphoning pipe, one end of which projects into the body of water, and the opposite end in a plane lower than the bed of the body of water, said latter end being restricted in diameter, a valve in said pipe at the water level, a second valve in said pipe at a point near the discharge end thereof, 100 a dredging pipe connected to the siphoning pipe at a point between the ends of the siphoning pipe and nearer the end entering

the water, a screen mechanism at the free end of the dredging pipe, a valve in the dredging pipe near the water level, a pump connected to said siphoning pipe between the 5 end thereof entering the water and the dredging pipe, a valve for connecting said pump with the siphoning pipe, a pipe con-

necting said pump with the body of water, and a valve in the siphoning pipe between said pump and dredging pipe, said valve 10 having an air vent.

In witness whereof, I have hereunto affixed my signature.

JACOB P. TETER.
